CLAIM

I claim the ornamental design for a pouch, as shown and described.

DESCRIPTION

FIG. 1 is a front, right, and top side perspective view of an ornamental design for a pouch, the pouch in a closed position;

FIG. 2 is a front side elevational view thereof;

FIG. 3 is a rear side elevational view thereof;

FIG. 4 is a top plan view thereof;

FIG. 5 is a bottom plan view thereof;

FIG. 6 is a right side elevational view thereof;

FIG. 7 is a left side elevational view thereof; and,

FIG. 8 is a front, right, and top side perspective of the pouch in an open position.

The dashed broken lines depict portions of the pouch that form no part of the claimed design. The dash-dot-dot broken lines depict environment, and form no part of the claimed design.
